APPARATUS FOR TESTING EXPANSION OF MOVABLE MEMBERS

Melvin Frankel and Walter Bradford Shank, Los Angeles, Calif., assignors to the United States of America as represented by the United States Atomic Energy Commission

Application July 2, 1947, Serial No. 758,498

4 Claims. (Cl. 73—52)

This invention relates to a testing system, and more particularly to a novel means for determining the expansion of an expandable movable member.

A general object of the invention is to devise a simple and inexpensive system for determining the expansion of a member snugly fitted within a container.

Another object of the invention is to provide a novel means for moving the member within its container and for measuring the frictional resistance between the member and the container by measuring the force under which the member moves.

The invention is particularly well suited to a neutronic reactor of the type employing cylindrical cartridges of fissionable material called "slugs," for detecting swelling in faulty slugs before damage is caused to the reactor. Thus another object of the invention is to provide a novel means for detecting faulty slugs in a neutronic reactor.

The foregoing and other objects and advantages of the invention will become apparent from a consideration of the following specification and the accompanying drawings, wherein:

Fig. 1 is a fragmentary central vertical cross sectional view partly in elevation of a device embodying the invention, in combination with a diagram illustrating a novel hydraulic system for actuating the device; and

Fig. 2 is a cross sectional view taken in the vertical plane indicated by the line 2—2 of Fig. 1.

The invention is illustrated as applied to a neutronic reactor generally designated 2 and comprising a mass 4 of neutron moderator such as graphite or beryllium. A tube 6 of neutron-permeable material having a relatively small neutron capture cross-section, such as, for example, aluminum or beryllium, extends through the moderator mass 4 and contains a plurality of aluminum-jacketed uranium slugs 8 disposed end-to-end extending through the moderator mass 4. One of the slugs B in Fig. 1 is illustrated partially in central vertical cross-section.

It will be understood that in actual practice a great number of tubes 6 containing slugs 8 are disposed within the moderator mass 4 to provide a reactive composition capable of sustaining a nuclear fission chain reaction. As a result of the nuclear fission chain reaction, considerable heat is developed within the slugs 8, and this heat is dissipated by a coolant, such as water, passed through the tube 6 by inlet and outlet conduits 10 and 12 connected to the tube by fittings 14 and 16, respectively. As will be clearly seen in Fig. 2, the tube 6 is provided with a plurality of longitudinal ribs 18 which bear against the slugs 8 to center the same within the tube, thereby affording an annulus 20 around the slugs to accommodate flow of the coolant, such as water, which is circulated as above described by means of inlet and outlet conduits 10 and 12.

It will be understood that leakage of the water through one of the slug jackets causes the same to expand inasmuch as the water reacts with the uranium to form uranium oxide which has a greater specific volume than uranium metal. This swelling of the slug 8 may cause the

same to become fixed within the tube 6, thus preventing removal of the slugs therefrom as is necessary from time to time to renew the slugs and recover products of the nuclear reaction. Furthermore, swelling of the slug may continue, blocking flow of water through the annulus 20, thereby preventing cooling of the other slugs within the tube and causing excessive heating.

Thus, it will be understood that in a system such as above described it is very important to determine from time to time whether any of the slugs 8 within the tube 6 have swelled. This determination is made by the novel apparatus disclosed in Fig. 1, said apparatus comprising cylinders 22 and 24 secured to opposite ends of the tube 6 by fittings 26 and 27, respectively. The cylinder 24 at the coolant inlet end of the tube contains a hollow piston 28 which is actuated by hydraulic fluid admitted to the cylinder 24 through a line 30. A plunger 34 is slidably fitted within the piston 28 in threaded engagement therewith as at 36, the outer end of the plunger being provided with a lock nut 38. Thus, it will be understood that by rotating the plunger 34, it may be adjusted relative to the piston 28 so that it properly bears against the row of slugs 8. For the latter purpose, there are likewise provided spacers 37 and 39, for example of stainless steel.

25 The cylinder 22 at the coolant outlet end of the tube 6 contains a piston 40 which is integrally formed with a plunger 41 bearing against the adjacent slug 8, said piston being actuated by hydraulic fluid admitted to the cylinder 22 by a line 42.

30 Thus, it will be understood that the row of slugs 8 is pushed back and forth within the tube 6 by means of the plungers 34 and 41, the plunger 41 having a relatively great diameter so that the total pressure exerted against the respective plungers by the coolant is approximately equal, inasmuch as the coolant pressure at the inlet end of the tube is greater than at the outlet end thereof. This facilitates measurement of the force necessary to move the slugs by measurement of the pressure in a common fluid supply line adapted to be alternately connected to the cylinders 22 and 24 as hereinafter discussed. As the slugs 8 are moved back and forth within the tube 6, swelling of any slug within the tube increases the resistance of the slugs to the force exerted thereagainst and is detected by measurement of that resistance.

35 40 The resistance to movement of the slugs by the development of friction between a swollen slug and the tube is measured as hereinafter described by the hydraulic actuation circuit associated with the cylinders 22 and 24. This circuit comprises a reservoir 46 containing a supply of any suitable hydraulic medium such as oil, said reservoir being connected by a line 48 to the suction side of a pump 50, the discharge side of which is connected to a supply line 52 having a surge tank 54 therein for the purpose of compensating for minor variations in the pressure exerted by the pump 50.

45 50 The line 48 is provided with a one-way check valve 56 accommodating flow of fluid to the pump 50 and is also provided with a drain valve 58 for draining the system. The line 52 is provided with a drain valve 60, and is connected to a relief or discharge line 62 through a throttle valve in the form of a conventional needle valve 64. Thus, by adjusting the throttle valve 64, a predetermined value is built up within the main supply line 52, said value being measured by a gauge 66 connected to the line 52 by a throttle valve 68 which is closed slightly, so that the valve 68 functions as a snubber to prevent violent movement of the gauge needle which might result in damage to the gauge. The line 52 is also connected through a conventional relief valve 70 to the before-mentioned discharge line 62, said valve 70 being adapted to open the line 52 to discharge upon the development therein of a predetermined maximum safe pressure value.

The line 52 is connected through a throttle valve 72 to a branch line 74 which is connected to a conventional three-position selector valve 76 adapted to selectively open the line 74 to communication with one of the lines 30 and 42 associated respectively with the cylinders 24 and 22 as heretofore described or, in the third or neutral position, to mutually interconnect the lines 74, 30, 42 and 62. The branch line 74 is provided with a surge tank 78 and a gauge 80 connected to the line 74 through a throttle valve 82 functioning as a snubber in the manner described in connection with the valve 68. The line 74 is also connected to the line 62 through a throttle valve 84 accommodating adjustment of pressure within the branch line 74 as hereinafter described.

It will be seen that the line 52, shown as heavy piping in Fig. 1, constitutes a constant high pressure portion of the system. The line 62 constitutes a discharge line which is always substantially at atmospheric pressure. The line 74 contains fluid which is made to vary in pressure from atmospheric pressure up to the constant pressure of the line 52. Operation of the device, other than preliminary adjustment, is accomplished by operation of the valve 76, all other valves being held in fixed position during operation. The valve 64 serves as an adjustment of the constant pressure in the line 52. This is so adjusted that the constant pressure in the line 52, as indicated by the gauge 66, is a suitable amount, for example 30 to 50 pounds per square inch, greater than the pressure required to move the row of slugs 8 against the frictional forces which are present in the absence of swelling on any of the slugs 8. When the valve 76 is in the neutral position, the lines 74, 30 and 42 are all substantially at atmospheric pressure. In this position, the total pressure drop between the constant pressure line 52 and atmospheric pressure occurs across the valve 72. When the valve 76 is then changed to a position disconnecting the discharge line 62 and connecting the line 74 to one of the cylinders 22 or 24, the pressure in the line 74, and thus in the cylinder 22 or 24, builds up at a rate which is dependent upon the position of the valve 72 and the valve 84. These two valves may be adjusted to give a desired build-up time for the pressure, the valve 84 being used for fine control.

In operation, the positioning of the valve 76 is cycled as follows: both cylinders 22 and 24 are fixed at atmospheric pressure by putting the valve 76 in its neutral position. The valve 76 is then placed in one of its other two positions. The pressure then builds up until the row of slugs 8 commences to move, as indicated visually, or by a motion-indicating device (not shown). The pressure, as indicated by the gauge 80, at which the row of slugs 8 commences to move may be recorded. Atmospheric pressure in the cylinders 22 and 24 and the line 74 is then again restored by placing the valve 76 in the neutral position. The valve 76 is then placed in the position to connect the line 74 to the other of the cylinders 22 or 24. The pressure again builds up, and again the pressure at which the row of slugs 8 commences to move may be recorded. This operation may be continued at regular intervals. For example, a total cycle may take 20 minutes, the row of slugs 8 thus being pushed every ten minutes. With such a cycling it is found desirable to adjust the valve 72 and 84 so that pressure in the cylinders 22 and 24 builds up to the point where motion occurs in about 5 minutes in

normal operation, i.e., where no swellings exist on the slugs 8. If a swelling develops on a slug 8, the pressure at which motion of the row of slugs 8 commences is greater than normal. Thus by periodic operation of the valve 76 in the manner described above, the existence of swellings on the slug 8 may be constantly monitored.

It will be understood that only one embodiment of the invention is illustrated and described above. Persons skilled in the art will readily devise equivalents utilizing the teachings of the invention, and will adapt the invention to use under various conditions of service.

What is claimed is:

1. An apparatus for testing the expansion of an expansible member within a tube comprising opposed pistons projecting into opposite ends of said tube, hydraulic motor means for alternately actuating said pistons to move said member back and forth within said tube, a source of pressure fluid connected to said means, and means for measuring the pressure of said fluid.
2. An apparatus for testing the expansion of an expansible member within a tube, comprising cylinders at opposite ends of said tube, opposed pistons within respective cylinder projecting into opposite ends of said tube and acting upon said member, a supply line containing pressure fluid, valve means for alternately exhausting said line and directing flow of said fluid into respective cylinders, and means for measuring the pressure in said line.
3. An apparatus for testing the expansion of an expansible member within a tube conveying fluid flowing in one direction therethrough, said apparatus comprising opposed pistons projecting into opposite ends of said tube, hydraulic motor means for alternately actuating said pistons to move said member back and forth within said tube, means for measuring the hydraulic pressure within each of said motor means, and means for exhausting each of said motor means prior to actuation thereof, the piston at the fluid outlet end of said tube having a greater diameter than the piston at the fluid inlet end thereof to equalize the pressure of said fluid against said pistons.
4. An apparatus for testing the expansion of an expansible member within a tube snugly engaging the member, comprising cylinders at opposite ends of the tube, plungers projecting into opposite ends of the tube, pistons within respective cylinders and operatively connected to said plungers for actuation thereof, said plungers being operatively connected to the member for moving the same back and forth within the tube, a fluid supply line, valve means for opening said line to communication first with one of the cylinders, then to discharge, and then to the other of the cylinders, and means for measuring the pressure built up in said line when the same is in communication with each of the cylinders.
